UNITED STATES PATENT OFFICE

EDWARD I. WILLIAMS, OF COPPERHILL, TENNESSEE

METHOD OF AND CONVERTER FOR BESSEMERIZING

Application filed April 22, 1929. Serial No. 357,000.

The present invention relates to improvements in metallurgic converters and method of operating same. More particularly the invention relates to improvements in converters for bessemerizing copper-bearing material and to their operation, whereby the life of the lining is prolonged.

In the bessemerizing of copper matte in a basic-lined converter, it has been found that the operation is attended by the erosion of the lining in the area at and above the tuyères and by building up of accretions on the lining on the side opposite the tuyères. This erosion and building up necessitates periodic repairs with consequent expense and loss of operating time.

An object of the present invention is to prolong the periods between shutdowns for repairs, thereby decreasing operating expenses due to repairs and increasing the effective operating life and output of the converter.

This end is attained by the alternate use of two sets of tuyères disposed on opposite sides of the converter in such relative relation one to the other that the erosion which takes place adjacent the one set during operation thereof is compensated for by the accretions which build up in such eroded zone during the operation of the other set of tuyères.

In the accompanying drawings, which illustrate diagrammatically the preferred embodiment of the invention:

Fig. 1 is an end elevation of the converter;

Fig. 2 is a transverse section of the converter taken through the charging and discharging opening; and

Fig. 3 is a section on a larger scale of a portion of the converter at one of the tuyères.

Referring to the drawings, the converter has the usual cylindrical metal body or shell 1, equipped with rings 2, that rest upon rollers 3, to support the vessel and allow for axial turning as may be necessary during treatment of the charge. The shell is provided with a continuous lining 4 of suitable material. The tuyères 5 of one set are arranged in a longitudinal series according to conventional practice at one side of the shell

and are suitably connected to an air blast distributing pipe 6 to which air is supplied from a header 9. The valve 7 provides a means for shutting off the air supply from the tuyères 5 when these tuyères are not in use. These tuyères 5^a of a second set are arranged in a longitudinal series on the opposite side of the shell from the tuyères 5. They are also connected to an air blast distributing pipe 6^a, flow through which may be shut off by the valve 7^a when the tuyères 5^a are not in use. The headers 9 and 9^a are shown as connected to a common air blast duct 11. The air distributing pipes 6 and 6^a are U-shaped and connected at both ends to their respective headers, thus promoting supply of air to all of the tuyères of each set under substantially the same pressure.

Fig. 3 shows a plug of clay 12 inserted in one of the tuyères 5^a. These plugs serve to prevent the molten material of the charge from entering the tuyères of the set which is not in use. An opening normally closed by a cap or other suitable closure 13 is provided at the rear end of each tuyère to permit of access thereto for forcing or drilling out the clay plug when it is desired to change from one set of tuyères to the other.

In determining the relative positions of the two sets of tuyères, the second set is positioned at or adjacent that zone in the wall of the converter opposite the first set upon which it has been proven, by previous experience with the material to be bessemerized, that accretions form during operation of the first set.

My using the two sets of tuyères alternately the building up of one side and the burning out or eroding of the other will be controlled, thus extending the life of the lining very materially. The interval necessary before transferring from one set of tuyères to the other will depend upon how fast the erosion of the lining at and above the tuyères in use and the building up on the lining at and above the tuyères not in use takes place. This time will depend upon the material treated in the converter whether matte or a mixture of matte and concentrate and on the températures involved. It is possible

that a change from one set of tuyères to the other once a month will be sufficient.

In the form of the converter shown in the drawing, which is particularly adapted for 5 use in treating copper matte and other copper-bearing materials, the converter will ordinarily be rotated to a position such that the imaginary line A—A will assume a vertical position when the tuyères 5 are in operation, and, vice versa, when the tuyères 5^a are brought into operation the converter will be rotated to the left until the line B—B approaches a vertical position.

When it is desired to use the second set of 15 tuyères, the ones then in use should be plugged with clay, for example, their air inlet valve closed and the second set of tuyères drilled out and their air inlet valve opened.

It is desirable that the converter be so arranged as to permit charging and discharging on either side dependent on which set of tuyères is in use. If it is not possible to make such an arrangement, provision may be made for turning the converter end for end so that 25 charging and discharging can always take place on the same side regardless of which set of tuyères is in use.

I claim:

1. In the operation of metallurgic converters, the method of preserving the lining which consists in alternately conducting the air blast first through one series of tuyères and second through another series of tuyères disposed on the opposite side of the converter.

2. In the bessemerizing of copper matte in converters, the method of preserving the lining which consists in alternately conducting the air blast first through one series of tuyères and second through another series of tuyères disposed on the opposite side of the converter.

3. In the bessemerizing of copper-bearing material in converters, the method of preserving the lining which consists in alternately conducting the air blast first through one series of tuyères and second through another series of tuyères disposed on the opposite side of the converter.

4. In the operation of metallurgic converters, the method of preserving the lining which consists in alternately conducting the air blast first through one set of tuyères until the lining has become eroded adjacent thereto, and then through another set of tuyères and causing the building up of accretions on the eroded portion of the lining by the influence of the blast from the second set of tuyères.

5. In the operation of metallurgic converters, the method of preserving the lining which comprises bessemerizing by introducing air under pressure until a zone of the converter wall under the influence thereof has become eroded, and then causing the building up of accretions on the eroded zone

by introducing air under pressure in a different portion of the converter.

In testimony whereof, I have signed my name to this specification this 15th day of April, 1929.

EDWARD I. WILLIAMS.
